UNITED STATES PATENT OFFICE.

GEORGE GUSTAVUS KITZEMAN, OF DES MOINES, IOWA.

COMBINATION POCKET-BILLIARD RACK AND REGISTER.

1,114,148.

Specification of Letters Patent.

Patented Oct. 20, 1914.

Application filed November 11, 1913. Serial No. 800,410.

To all whom it may concern:

Be it known that I, GEORGE G. KITZEMAN, a citizen of the United States, and a resident of Des Moines, in the county of Polk and State of Iowa, have invented a certain new and useful Combination Pocket-Billiard Rack and Register, of which the following is a specification.

The object of my invention is to provide a combination pocket billiard ball rack and register of comparatively simple, durable and inexpensive construction.

A further object is to provide a device of the kind mentioned, adapted to be operated by the deposit of coins or slugs.

Still a further object is to provide such a device, so constructed and arranged that it may be adjusted to be operated by any predetermined number of coins or slugs so that when the device is set it requires one, two or more coins or slugs to render it operative, as the case may be.

Still a further object is to provide a coin or slug controlled device of the kind mentioned, adapted to register each coin or slug deposited in the machine.

Still a further object is to provide such a device, having means whereby when a predetermined number of coins or slugs are inserted in the machine, a collapsible triangle or rack will be raised from a position under the table to proper position on the table for racking up the balls.

Still a further object is to provide such a device including means whereby the number of games played on a pocket billiard table may be registered.

My invention consists in certain details, in the construction, combination and arrangement of the various parts of the device, whereby the objects contemplated are attained, as hereinafter more fully set forth, pointed out in my claims, and illustrated in the accompanying drawings, in which:

Figure 1 shows a perspective view of a pocket billiard table, equipped with a combination pocket billiard ball rack and game and price register, embodying my invention. Fig. 2 shows a horizontal, sectional view of the case containing the registering mechanism and the mechanism therein, taken on the line just below the horizontal partition in said case. Fig. 3 shows a vertical, sectional view taken on the line 3-3 of Fig. 4. Fig. 4 shows a vertical, sectional, detail view, taken on the line 4-4 of Fig. 2. Fig.

5 shows a top or plan view of the casing of my coin registering device and a portion of the table rail above it. Fig. 6 shows a detail view of a portion of the collapsible triangle or rack. Fig. 7 shows a detail, sectional view of a portion of the rack controlling mechanism. Fig. 8 shows a detail, sectional view, taken on the line 8-8 of Fig. 7. Fig. 9 shows an end elevation of a portion of the table and the rack controlling mechanism. Fig. 10 shows a vertical, sectional view through the end of the table, illustrating the manner in which the rack controlling mechanism is mounted thereon. Fig. 11 shows an end elevation of a portion of the table with the rack in its lowered position, and Fig. 12 shows a detail view of part of the casing for the coin controlled mechanism, showing the indicating characters.

In the accompanying drawings I have used the reference numeral 10 to indicate generally a pocket billiard table of ordinary construction, on which is installed my combination pocket billiard ball rack and register. My game and coin registering mechanism is included within a casing having vertical side members 11, end members 12 and top and bottom members 13 and 14. Resting upon the casing just mentioned is a smaller casing 15. As shown in Fig. 3, the bottom member 14 does not extend to what I will call the rear end of the large casing, so that a space is left between the rear end of the bottom member 14 and the rear casing wall 12, the purpose of which will be hereinafter more fully explained.

Mounted to slide longitudinally in the larger casing is a frame 16. Depending from the frame 16 are a plurality of parallel plates 17, 18, 19 and 20. In each of the plates just mentioned is a slot 21. The slots 21 are so arranged that they have a horizontal portion at their rearward ends, then an upwardly and forwardly extending portion and then another horizontal portion, as clearly shown in Fig. 3. The upwardly and rearwardly extending portions of the slots 21 are arranged successively nearer the rear end of the large casing, as shown in Fig. 3. The ends of the plates 17 below the open ends of the slots 21 are formed with transverse grooves 22, as shown in Fig. 3, for the purpose hereinafter to be made clear.

Suitably mounted near the lower portion of the larger casing is a transverse shaft

23 and another transverse shaft 24 is mounted parallel therewith, above the level of the shaft 23 and rearwardly in the casing therefrom. Slidably mounted on the shafts 23 and 24 are the side members 25 of a transversely slidable frame. The frame members 25 are connected at their rear ends by a plate or wall 26. Secured to the upper portion of the wall 26 is a frame 27, in which 10 is formed a plurality of slots 28 to receive coins or slugs. The wall 26 is curved from its upper end downwardly and slightly forwardly, as shown in Fig. 3. The width of the slots 28 is just sufficient to receive the 15 coin or slug of the size adapted to actuate the machine.

Pivottally mounted at points between their ends on the shaft 24 are a plurality of arms or levers 29. On the forward ends of the 20 levers 29 are laterally extending cylinders 30. The levers 29 are so proportioned that they normally stand in position with the cylinders 30 on the level with the slots or grooves 22. The rear ends of the levers 29 25 extend upwardly and rearwardly from the shaft 24 and formed on the rear end of each of the levers 29 is a slot 31, shown by the dotted lines in Fig. 3, and designed to receive the edge of the coin or slug 32. The 30 levers 29 are so balanced that when the coin 32 is dropped through the slot 28 and is received between the wall 26 and the slot 31, the weight of the coin is enough to depress the rear end of the lever 29 and to 35 spring the cylinder 30 upwardly until it is on a level with the open ends of the slots 21. In the wall 26 are a plurality of vertically arranged slots 33, below the respective slots 28.

40 Assuming that the coin which is designed to be used in the machine is an ordinary five cent piece or slug of the same size, then the slots 33, Fig. 2, are so proportioned that at their upper end they are too narrow to 45 permit the five cent piece to pass through them. A dime or penny, however, instead of resting in the slot 31, Fig. 2, and being held by the wall 26, Fig. 3, would pass through one of the slots 33, Fig. 2, and be thereby 50 removed from the slot 31, so that the mechanism could not be worked with a coin or slug other than that for which it is expressly designed. The lower portions of the slots 33, Fig. 2, are of sufficient width to 55 permit the coin or slug of exactly the same proportion to pass through when the mechanism is operated as will be hereinafter more fully described. Suitably mounted below and rearwardly from the shaft 24, Fig. 2, 60 is a transverse shaft 34, on which is a toothed cylinder 35 and a toothed wheel 36. The cylinder 35 is provided with ratchet teeth 37, preferably twenty in number. A plurality of pawls 38 are arranged to coact 65 with the teeth 37 of the toothed cylinder

35 and to slide horizontally in the machine in guide devices 39. Extending upwardly from the rear end of the bottom member 14 is a frame member 40. Extending upwardly and forwardly from the upper end 70 of the member 40 is another frame member 41, the forward end of which is below the lower end of the wall 26.

For yieldingly holding the pawls 38 in engagement with the teeth of the cylinder 75 35 I have secured to said pawls and to the wall member 40, respectively, a plurality of contractible coil springs 42. Formed on the front end of the pawls 38 are downwardly extending lugs 43, designed to engage the 80 guide device members 39 for limiting the rearward movement of said pawls and leaving necessary play for the lugs 45, hereinafter mentioned, so as to permit their free lateral movement. Also to enable the cylinder 30 to clear the groove 22 for action after being counterbalanced. Formed on the forward end of said pawls are upwardly extending lugs or catch devices 44. Formed on the levers 29 are downwardly extending 85 lugs 45, designed to selectively engage the catch members 44 in the manner hereinafter more fully set forth. Pivottally connected with the frame 16 is a rearwardly extending link 46. Pivoted to the link 46 near its rearward end is a downwardly extending lever 47 in the lower end of which is an elongated slot 48, in which is received a pin 49. The lever 44 is centrally pivoted on a stub shaft 50. Pivottally mounted between its ends on 100 the stub shaft 50 is a controlling lever 51, Fig. 11, the lower end of which carries the pin 49. Pivottally mounted on the pin 52, Fig. 3, is a bell crank lever 53, one arm of which carries a roller 54, which engages the 105 toothed wheel 36. Secured to the downwardly extending arm of the lever 53 is a coil spring 55, for yieldingly holding the roller 54 in engagement with the wheel 36.

110 The tendency of the parts just described is to cause the shaft 34 to move exactly the same distance when moved by any one of the pawls 38. Should the pawls 38 not move the shaft 34 the proper distance, the roller 54 will press toward the middle point between two of the teeth of the wheel 36, for controlling the distance which the shaft 34 moves. On the cylinder 35 is a projection 115 56. Mounted within the casing, at the rear end thereof, is a registering device 57, on the shaft 58. The registering device 57 is operated by means of a lever 59 and a link 60.

120 The forward end of the link 60 is pivoted to a link 61 and stands in the path of the projection 56. The link 61 is pivoted to the frame member 41. The indicating device 57 carries ordinary indicating characters 62, which are visible through the slot 63 in the rear wall 12. Mounted within the 125 130

casing, adjacent to the rear wall 12, is another indicating device 64, mounted on the shaft 65 and operated by means of a lever 66 and a link 67. The link 67 is pivoted at one end to the lever 66 and at the other end to a short link 68. The link 68 is also pivoted to the frame of the casing. For holding the link 67 at the forward position of its movement, I have provided a coil spring 69. For moving the frame 25 laterally within the casing there is formed on the lower portion of the frame members 25 a horizontal rack bar 70, Fig. 3. Suitably mounted within the casing is a shaft 71, having one end angular at 72 to receive a guide or key. On the other end of the shaft 71 is a gear 73 in mesh with the teeth of the rack bar 70. The front wall 12 is provided with an opening 74 to receive a key for operating the shaft 71. On the shaft 71 is mounted a cam wheel 75, Fig. 6, provided with notches 76 in its periphery. Pivoted to the frame of the casing is an arm 77, on the free end of which is a roller 78, which is 25 yieldingly held in engagement with the cam wheel 75 by means of a spring 79. The cam wheel is so shaped that when the roller 78 is properly centered in one of the notches 76 and the shaft 71 is rotated the proper 30 distance for moving the frame 25, Fig. 3, a sufficient distance to move one of the rollers 30 from its position adjacent to one of the notches 22 to position adjacent to the next succeeding notch 22, the roller 78, Fig. 6, 35 will then be centered in the next notch 76. I am thereby enabled to speedily move the frame members 25, Fig. 3, the proper distance, precisely and accurately by means of the key operating the shaft 71.

40 I shall now describe the practical operation of my coin registering device and will thereafter describe the construction and operation of the rack or triangle controlling mechanism. The parts of my device are so 45 built that the carriage members 25 may be moved entirely to one side until the rollers 30 are clear of the plates 17. The lever 51 may then be operated as often as desired, without the use of coins or slugs. To set 50 the machine for operation by any number of slugs or coins, the shaft 71 is turned by means of a key until one or more of the rollers 30 are opposite one or more of the slots or grooves 22, to correspond to the 55 given number of participants in the various games of pocket billiards, commonly called pool. Assuming for the purpose of illustration that the machine is desired to be set for operation by means of one coin or slug, 60 then the frame members 25 are moved until one of the rollers 30 is opposite the first plate 17, as shown in Fig. 2. In this connection it may be noted that the slots 28, may, if desired, be provided with inwardly 65 extending lugs 80 and that slots or grooves 81 of proper size to receive the lugs 80 may be formed in slugs used in the machine. Assuming that a slug of the size of a five cent piece, or a five cent piece, is being used, and that the machine is used for coins or 70 slugs of that size, the cover member 13 is provided with an opening 82, of such size that all of the slots 28 may be below said opening. The frame members 25 carry a plate 84, which fills the space beneath the 75 opening 82, when the members 25 are moved to position where none of the rollers 30 are opposite the grooves 22. When the members 25 are moved laterally to the position assumed above, the first of the slots 28 is 80 within the opening 82 and the rest of the opening 82 is closed by the plate 84. When the slug or coin is dropped through the first slot 28 it is received in the cover or slot 31 of the first lever 29 and rests against the 85 member 26. The weight of the coin is sufficient to depress the rear end of the lever 29 and to raise the forward end thereof until the cylinder 30 is opposite the first cam slot 21. The lever 51 is then seized and moved 90 rearwardly, thereby moving the frame 16 rearwardly and causing the cylinder 30 to travel upwardly in the cam slot. The downward extension 45 is thereby moved to the point where it engages the catch member 44 95 and draws the pawl 38 forwardly, moving the cylinder 35 one notch. On the outer end of the shaft 34 is a dial on which are indicating numerals 85. The dial carrying the indicating numerals 85 is received within 100 the casing 86, in which is a slot or opening 87. The numerals 85 indicate the number of coins that have been deposited in the machine. The coin is discharged through the slots in the lower portion of the member 26 and drops downwardly along the inclined member 41 into a coin receptacle 88, below the large casing. The coin receptacle 88 has a hinged door 89, secured by a lock 105 90. It will readily be seen that by moving the members 25 to position where two of the cylinders 30 are opposite two of the grooves 22, it will require two coins or slugs to operate the machine. In that case, two of the extensions 45 would be opposite two of the 110 catch devices 44 and two of the pawls 38 would be operated to move the cylinder 35 the distance of two notches. When a certain number of coins have been deposited and the machine has been operated to move 115 the toothed cylinder often enough to make one complete revolution, which in the case of the machine illustrated in the drawings, would be twenty movements, or twenty pawl operations, the extension 56 engages the link 60, thereby operating the registering device 57 for showing that the shaft 34 had made a complete revolution and that coins or slugs indicating the value of one dollar 120 have been deposited in the machine. 125 130

I will now describe the construction and operation of the parts of the machine which control the triangle or rack. Rotatably mounted in the upper smaller casing 15, Figs. 4 and 5, is a shaft 91, which extends beyond the casing 15. Mounted on the shaft 91 within the casing 15 and secured to the shaft at one end and to the casing at the other end, is a powerful coil spring 92. 5

10 Mounted on said shaft within the casing 15 is a sleeve 93, having a downwardly extending arm 94, which passes through the slot 96 into the lower casing. Secured to one of the walls 11 is a flat spring 95 which extends 15 transversely across the upper portion of the larger casing and is provided with a shoulder 97 designed to engage the arm 94. Fixed on the outer end of the shaft 91 is a plate 98, having bifurcated arms 99, on 20 which are formed bearings 100 fixed to the shaft 91. The shaft 91 is placed below the rail top 101 of the pocket billiard table 10. The plate 99, Fig. 11, is provided with a groove 102 to receive the edge of the top rail 101 when said plate is raised. Hinged 25 to the plate 98, just above said groove, is a second plate 103. Extending outwardly from each arm 99, when the latter are in their raised position, are posts 104, on the outer ends of which are sleeves 105, to 30 which are pivoted arms 106. When the plate 98 is in its raised position, the arms 106 extend upwardly parallel with each other, as shown in Fig. 9. Pivoted to the plate 103 are the arms of a lazy tongs lever 107. Said arms extend beyond their pivotal point and carry sleeves 108. The sleeves 108 are formed with flat faces 109, which correspond with flat faces 110 on the 35 sleeves 109, on the outer ends of the arms 106. The respective sleeves 108 and 111 are pivoted together. Mounted on the lazy tongs lever 107 are a plurality of springs 112, which normally tend to move the lazy 40 tongs lever to its open position. Formed on each of the sleeves 105 is a lever 113, which extends upwardly and outwardly when the plate 98 is in its raised position, as shown in Fig. 9. Formed on the plate 103 45 is an arm 114, which extends rearwardly when the plate 103 is in its upper horizontal position, above the table rail. Pivoted to the arm 114 and extending downwardly therefrom when said arm is in the position 50 shown in Fig. 9 is a rod 115. On the rod 115 is slidably mounted a collar 116, to the opposite sides of which are pivoted links 117. The outer ends of the links 117 are pivoted to the outer ends of the levers 113. The lower end of the shaft 115 is screw-threaded and carries a nut 118. Mounted 55 on the shaft 115, between the nut 118 and the collar 116 is an expansible coil spring 119. The spring 119, shaft 115, the links 117 and levers 113 serve to control the lazy tongs

levers so that when they operate to place the triangle hereinafter described on the table, the said lazy tongs levers move on a line of the central longitudinal axis of the table. Extending rearwardly from the plate 98 is 70 a guide device 120, so located and arranged that when the plate 98 and the plate 103 are moved from their open extended position with the rack on the table, upwardly and back toward vertical position, the arms of 75 the lazy tongs lever back of the pivotal points thereof, on the plate 103, engage the sides of said guide device and when the plate 103 and said lever reach vertical position, the arms mentioned engage the notches 80 in the sides of the guide device and thereafter the lazy tongs lever cannot be extended. The guide device 120, the rods 106 and the levers 113 and parts connected therewith are so arranged that the lazy tongs lever 85 cannot be extended until the plate 103 is dropped almost to horizontal position above the rail. When the plate 103 is in such position, the ends of the lazy tongs lever will be freed from engagement with the guide 90 device 120 and the lever may open. At the opposite end of the lazy tongs lever 107 from the plate 103, the ends of the lever members are pivoted in the walls of the casing 121, Fig. 11. Secured to one edge of 95 the casing 121 is one side 122 of a triangle. Hinged to the ends of the side 122 are the other sides 123 and 124, Fig. 1, of the triangle. The sides 123 and 124 are also hinged together and the side 124 is made 100 of two parts connected by an inwardly folding hinge 125.

The casing 121 is formed with longitudinal grooves or guides 126, Fig. 8, in its top and bottom walls. In the grooves 126, adjacent to the side 122, Fig. 7, is slidably mounted a rack bar 127. Pivots connected with the rack bar 127 are links 128. The links 128 are pivotally connected to the pivoted ends 129 of the lazy tongs lever. Between the rack bar 127 and the end of the casing 121, opposite the side 122 of the triangle or rack, are extensible coil springs 130. Pivotally mounted within the casing is a sector 131, in mesh with the teeth of the rack bar 127. 115 Slidably mounted in one side of the casing 121 is a bar 132 formed on the inner end of which is a rack bar 133, in mesh with the sector 131. Formed on the casing 121 is a small cylinder 134, which is hollow and receives at one end a screw plug 135. The bar 132 is extended through the cylinder 134 longitudinally. On the bar 132 within the cylinder 134 is a collar 136. On each side of the collar 136 within the cylinder 134 are 120 coil springs 137. On the outer end of the bar 132 is a rack bar 138, which travels in a guide 139 secured to the rack member 122. Secured in the rack member 124 is a sector 125 140, in mesh with the rack bar 138. 130

Assuming that the rack and lazy tongs lever are in their lower position, as shown in Fig. 11, the operation thereof is as follows: When the member 46 strikes the spring 95 and releases the extension 94, the spring 92 rotates the shaft 91, swinging the lazy tongs lever and the parts connected therewith upwardly until they first stand in substantially vertical position above said shaft 91. The 5 groove 102 receives the edge of the rail and the plate 103 tips downwardly over the top of the rail, by the instantaneous momentum just received and by gravity of the lazy tongs lever and the triangle and its accessories. When the lazy tongs lever reaches a position almost horizontal and parallel with the table, the arms 106 move upwardly away from the guide devices 120 and the springs 112 open the lazy tongs lever, which 10 carries the rack outwardly and over the table, the required distance. When the lazy tongs lever opens, the ends 129 move away from each other within the casing 121, moving the rack 127 away from the plate 103 and through the sector 133, the bar 132 and the sector 140, the triangle or rack is opened. The balls may be racked up on the table and the attendant can then seize the rack and pull it toward the plate 103, collapsing the 15 lazy tongs lever and the rack, simultaneously lifting the rack and lazy tongs lever to a vertical position, when the guide device 120 will engage the rods 106 and 107 and prevent further opening of the lazy tongs lever. 20 The said lever and the rack and plate 103 may be raised to vertical position and the whole mechanism above the shaft 91 may then be tipped outwardly and downwardly, thereby rotating the shaft 91 until the spring 25 95 again engages the extension 94 and the device may not again be operated until properly compensated with the required number of slugs or coins.

As will be seen from the foregoing description, my improved device has a large number of advantages. By using my improved device, the owner of the establishment is enabled to keep close check on his customers and also on the employees who 30 take care of the tables during the playing.

When the game is started, the attendant may rotate the shaft 71 so that if desired the machine may be operated without the necessity of depositing any coins or slugs therein. If, however, it is desired to make the paying device automatic, the shaft 71 may be rotated to move the carriage or frame, which includes the coin receiving device, to the position where any desired predetermined number of coins or slugs are required for operating the machine before each game. It should be noted in this connection that while the device has been shown constructed for operation by a maximum of 35 four parts or slugs, the parts may be read-

ily duplicated so that a larger number may play and use the machine by depositing a larger number of coins. In this connection, attention is called to the fact that slugs with grooves in their surface may be employed, the grooves being arranged to correspond with lugs in the receiving slots so that nothing but the particularly prepared slug could be used in the machine. By slightly varying the position of the lugs and slots just mentioned, the machines may be so constructed that in one locality each machine will require its particular slug and the slugs are not interchangeable. If coins are used, the machine is so constructed that only the particular proper coin may be used. When the proper number of coins is deposited, the levers 29 are moved to proper position for presenting the extensions or cylinders 30 to the slots 21. The portions of 40 the plates 17 above the slots are extended over the slots so as to engage the cylinders 30 should the ends of the levers 29 move too far upward. Attention is called to the fact also that there is plenty of play between the downward extension 35 and the pawl 38 and the member 44 to permit the free operation of the parts. When the proper number of coins have been deposited and the lever 51 is operated, the coins drop 45 rearwardly upon the member 41 and are deposited in the coin receptacle 88, from whence they may be removed at any time. When the lever 51 is operated, the rearward movement of the arm 46 is such as to cause it to engage the spring 95 and move the latter out of engagement with the arm 94. The parts then operate in the manner hereinbefore described to place the triangle 50 in the proper place on the table.

It is believed that a proper system to work with my machine would be to have the attendant carry an extra basket of balls, placing them in the triangle or rack when a new game is started so that the players may 55 go on with the game and the attendant may take the balls out of the pockets or the wall racks at his leisure.

It will be seen that there is considerable saving of the players' time, enabling a 60 larger number of games to be played and thereby increasing the profits of the owner. At the same time, it is unnecessary to have any special system for collecting or keeping accounts in connection with each table. By 65 checking up the various dials every morning, each day's receipts may be accurately ascertained.

Attention is called to the fact that the 70 whole device is secured to the under side of the table so as not to mar the exposed parts in any way. The parts are so located and arranged that when the rack and the parts connected therewith swing downwardly the 75 inwardly projecting parts are just below the 80

table rail. The arms 99 and bearings 100 are so mounted on the shaft 91 and with relation to the parts which are secured to the table as to prevent the parts from striking the rail body or the top rail. In the plate 103 I have provided openings designed to selectively receive a pin 200 for limiting the opening movement of the lazy tongs lever and thereby regulating the distance of the triangle from the table rail.

By requiring players to pay in advance, the billiard hall owner is enabled to comply with the anti-gambling statutes.

In the following claims, I intend to term 15 "coin" to cover coins or slugs of any kind.

It will be understood that a great many changes may be made in the details of the construction of my device and in the proportion and arrangement of the parts, material used and so on, and in means for accomplishing the various purposes of my device, and it is my intention to cover by this application any such changes which may be included within the scope of the following 25 claims:

I claim as my invention:

1. In a device of the class described, a coin controlled mechanism, means for adjusting said mechanism so that it may be controlled by one or more coins, means whereby the number of coins deposited in the machine may be indicated, and means whereby the number of operations of the machine may be indicated regardless of the 35 number of coins deposited at each operation.

2. In a device of the class described, a coin controlled mechanism including a casing, a slideable coin receiving frame, having coin receiving openings, a plurality of 40 levers, each provided with a coin receiving slot below one of said openings, a toothed cylinder, pawls operatively connected therewith, and means whereby said levers may be operated for moving said pawls and operating said cylinder, said means being so constructed and arranged that one or more of said pawls is operated, depending upon the position of said sliding frame.

3. In a device of the class described, a 50 coin controlled mechanism including a casing, a frame slideable therein, having coin receiving openings, levers pivoted between their ends below said openings, said levers having at one end coin receiving means, a second frame slideably mounted, and means thereon for successively engaging and moving one or more of said levers when said second frame is moved toward the first frame.

4. In a device of the class described, a 60 coin controlled mechanism including a casing, a frame slideable therein, having coin receiving openings, levers pivoted between their ends on said frame below said openings, said levers having at one end coin re-

ceiving means, a second frame slideably mounted, means thereon for successively engaging and moving one or more of said levers when said second frame is moved, said levers being arranged to stand normally 70 out of position to be engaged by said last named means, and to be moved to position for such engagement when coins are dropped upon said levers.

5. In a device of the class described, a 75 coin controlled mechanism including a casing, a frame slideable therein, having coin receiving openings, levers pivoted between their ends on said frame below said openings, said levers having at one end coin receiving means, a second frame slideably mounted, means thereon for successively engaging and moving one or more of said levers when said second frame is moved, said levers being arranged to stand normally 80 out of position to be engaged by said last named means, and to be moved to position for such engagement when coins are dropped upon said levers, said frames being so arranged that the position of the first frame 85 determines the number of levers operated.

6. In a device of the class described, a 90 coin controlled mechanism including a casing, a frame slideable therein, having coin receiving openings, levers pivoted between their ends on said frame below said openings, said levers having at one end coin receiving means, a second frame slideably mounted, means thereon for successively engaging and moving one or more of said 95 levers when said second frame is moved toward said levers, said levers being arranged to stand normally out of position to be engaged by said last named means, and to be moved to position for such engagement when coins are dropped upon said levers, said frames being so arranged that the position of the first frame 100 determines the number of levers operated, said casing being provided with a coin opening, and means for closing said opening except to permit the admission of a number of coins required to operate the device according to 105 the position of said first frame.

7. In a coin controlled mechanism, a 110 casing, a frame in said casing having coin receiving openings, a plurality of levers below said openings mounted on said frame, a second slideably frame therein, a plurality of lever operating means thereon, said first 115 frame being arranged to bring one or more of said levers to position adjacent to one or more of said lever operating means, said casing being provided with an opening arranged to expose the coin receiving openings corresponding with the levers to be 120 operated.

8. In a coin controlled mechanism, a 125 casing, a frame in said casing having coin receiving openings, a plurality of levers be- 130

low said openings mounted on said frame, a second slideable frame therein, a plurality of lever operating means thereon, said first frame being adapted to be moved to different positions to bring one or more of said levers to position adjacent to one or more of said lever operating means, said casing being provided with an opening arranged to expose the coin receiving openings corresponding with the levers to be operated, and means carried by said first frame for closing the opening in said casing except for admitting the proper number of coins to correspond with the number of levers in position to be operated.

9. In a device of the class described, a coin controlled mechanism including a casing, a frame slideable therein, having coin receiving openings, levers pivoted between their ends below said openings, said levers having at one end coin receiving means, a second frame slideably mounted, means thereon for successively engaging and moving one or more of said levers when said second frame is moved, the number of levers operated depending on the position of the first frame, said levers being arranged to stand normally out of position to be engaged by said last named means, and to be moved to position for such engagement when coins are dropped upon said levers, and means for adjusting the position of said second frame.

10. In a device of the class described, a coin controlled mechanism including a casing, a frame slideable therein, having coin receiving openings, levers pivoted between their ends below said openings, said levers having at one end coin receiving means, a second frame slideably mounted, means thereon for successively engaging and moving one or more of said levers when said second frame is moved, said levers being arranged to stand normally out of position to be engaged by said last named means, and to be moved to position for such engagement when coins are dropped upon said levers, said frames being so arranged that the position of the first frame determines the number of levers, by bringing the proper number of levers opposite the selective operating means of the second frame.

11. In a device of the class described, a coin controlled mechanism including a casing, a frame slideable therein, having coin receiving openings, levers pivoted between their ends below said openings, said levers having at one end coin receiving means, a second frame slideably mounted, means thereon for successively engaging and moving one or more of said levers when said second frame is moved, said levers being arranged

to stand normally out of position to be engaged by said last named means, and to be moved to position for such engagement when coins are dropped upon said levers, said frames being so arranged that the position of the first frame determines the number of levers operated, by bringing the proper number of levers opposite the selective operating means of the second frame, and means for moving said first frame for locating it in various proper positions.

12. In a device of the class described, a coin controlled mechanism including a casing, a frame slideable therein, having coin receiving openings, levers pivoted between said ends below said openings, said levers having at one end coin receiving means, a second frame slideably mounted, means thereon for successively engaging and moving one or more of said levers when said second frame is moved, said levers being arranged to stand normally out of position to be engaged by said last named means, and to be moved to position for such engagement when coins are dropped upon said levers, said frames being so arranged that the position of the first frame determines the number of levers operated, by bringing the proper number of levers opposite the selective operating means of the second frame, and means for moving said first frame for locating it in various proper positions, said means comprising a toothed bar on said first frame, a shaft, a toothed wheel thereon in mesh with said bar, a notched wheel on said shaft, and a spring controlled roller designed to enter the notches in said wheel when the first frame is in one of its proper positions.

13. In a coin controlled mechanism, a casing, a longitudinal slideable frame therein, a transversely slideable frame therein, the frames being each provided with a plurality of coacting and engaging devices so arranged that the number of engaging devices on the first frame adapted to be engaged by the devices on the second frame depend upon the sliding position of the first frame, the engaging devices on the second frame being arranged to normally stand in the path of the parts of the first frame when the second frame is in position for coacting with the first frame, and being designed to be operated by coins to be moved to position for coacting with the engaging devices on the first frame.

Des Moines, Iowa, November 6, 1913.

GEORGE GUSTAVUS KITZEMAN.
